US0D1104018S

(12) **United States Design Patent** (10) **Patent No.:** **US D1,104,018 S**
(45) **Date of Patent:** **** Dec. 2, 2025**

(54) **ELECTRONIC DEVICE WITH GRAPHICAL USER INTERFACE**

(71) Applicant: **Apple Inc.**, Cupertino, CA (US)

(72) Inventors: **Jody Akana**, Los Altos Hills, CA (US); **Marcos Alonso Ruiz**, Oakland, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Daniele De Iuliis**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Joe Tan**, Vienna (AT); **Clement Tissandier**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/900,284**

(22) Filed: **Aug. 18, 2023**

Related U.S. Application Data

(63) Continuation of application No. 29/749,382, filed on Sep. 4, 2020, now Pat. No. Des. 999,775, which is a

continuation of application No. 29/616,893, filed on Sep. 10, 2017, now Pat. No. Des. 895,639.

CLAIM

The ornamental design for an electronic device with graphical user interface as shown and described.

DESCRIPTION

FIG. 1 is a front view of an electronic device with graphical user interface showing the claimed design; and, FIG. 2 is a front view of an alternate electronic device with graphical user interface.

The outer broken lines in the figures show an electronic device, and form no part of the claimed design. The other broken lines in the figures show portions of the graphical user interface that form no part of the claimed design.
